OXYGEN GENERATING APPARATUS

Albert Hloch, Bitterfeld, Germany, assignor to I.
G. Farbenindustrie Aktiengesellschaft, Frank-
fort-on-the-Main, Germany

Application March 9, 1937, Serial No. 129,822
In Germany November 5, 1931

3 Claims. (Cl. 23—281)

This invention relates to apparatus for generating oxygen by thermal decomposition of oxygen-liberating compositions, more particularly for use in connection with rescue apparatus.

In such known oxygen-generating apparatus, the oxygen-generating mixture of chemical substances, consisting for example predominantly of chlorate and/or perchlorate, is generally employed in the form of a shaped compressed body disposed in a sheet metal container which is provided with an ignition device.

The present invention aims at providing an ignition device for such oxygen-generating apparatus which is simple in construction and operation, which will not transmit sparks to the outside and which is sufficiently rigid to withstand the high pressure of the ignition gases and the thermal stresses set up by the exothermic reaction by which the oxygen is liberated.

The device of the present invention is particularly intended for use in conjunction with oxygen-generating apparatus of the foregoing type, in which the shaped body of oxygen-generating composition is snugly disposed in a cartridge casing and held firmly and secure against shock by means of a heat insulating and filtering sheathing enclosing it on all sides, in the manner described in application Ser. No. 78,612, filed May 8th, 1936, and bearing the title "Apparatus for generating oxygen".

With the foregoing and other objects in view the present invention provides in oxygen-generating apparatus of the foregoing type, an ignition device comprising a rigid lid in which an ignition cap is inserted and which is secured to one end of the sheet metal cartridge containing the oxygen-generating composition, and a resilient cover for said lid.

In order that the invention may be more readily understood, reference is made to the accompanying drawing which illustrates diagrammatically and by way of example two embodiments thereof and in which:—

Fig. 1 is a longitudinal section through one embodiment; and

Fig. 2 a partial longitudinal section of a second embodiment.

In the embodiment shown in Fig. 1, the oxygen-generating composition B in the form of a compressed cylindrical body having a recess accommodating a primer B₁ is inserted in a sheet metal container A with the primer B₁ upwards, in such a way that it is surrounded on all sides by a sheathing K of heat-insulating and filtering filling material. At the lower end the filling ma-

terial rests on a layer J of asbestos fibre, which in turn rests on a wire sieve H. The oxygen generated passes through an outlet aperture G provided in the lid C.

The ignition device consists of a lid D₁ which carries an ignition cap F and a domed attachment D₃ secured thereto by rivets or the like and resting on the cylindrical body of oxygen-generating composition. By virtue of this arrangement the flame occurring during ignition is directed away from the walls of the sheet metal container A and towards the sheathing K. The lid D₁ and the domed attachment D₃ must be as rigid as possible in order to prevent yielding of the ignition cap F. Disposed above the ignition cap is a striking pin E which is guided by a guide E₁ and on which lies a thin-walled resilient cover D₂, which is preferably provided with grooves or the like to give extra resiliency. Said cover D₂ serves as an additional seal to prevent the escape of gas when the ignition cap F is fired, but it must be sufficiently resilient to transmit a blow thereon to the striking pin E. The lid D₁ and cover D₂ are secured to the sheet metal casing A in a gas-tight manner, preferably by welding, e. g. spot-welding.

The apparatus is operated by striking the centre of the cover D₂ with the aid of a striker, hammer or the like, the denting of the cover being favored by the grooves provided thereon. The striking pin E then ignites the ignition cap F, which latter in turn ignites the primer B₁ disposed in the cylindrical body B, which then generates oxygen by thermal decomposition.

In order to avoid unintentional operation of the oxygen-generating apparatus by accidental striking of the cover D₂, the striking pin E may be removably arranged as shown in Fig. 2. As shown in this figure, the striking pin E is screwed into a guide E₁ in such a manner that it can be screwed back or removed entirely and screwed down until its point touches the ignition cap F only when required to be used. A conical packing (not shown) may be provided to seal the cover D₂ in gas-tight manner.

I claim:—

1. An ignition device for oxygen-generating apparatus of the type in which chemical substances generating oxygen by thermal decomposition are employed in the form of a shaped body disposed in a container, said ignition device comprising an ignition cap and striking means adapted to coat therewith, a rigid lid closing said container and having said ignition cap disposed therein, a dome-shaped member secured to the

inside of said lid and adapted to repose with its rim on said shaped body disposed in said container, and a resilient cover for said lid held by the walls of said container and adapted, on being struck, to cause actuation of said striking means.

2. An ignition device for oxygen-generating apparatus of the type in which chemical substances generating oxygen by thermal decomposition are employed in the form of a shaped body disposed in a container, said ignition device comprising an ignition cap and a striking pin adapted to coact therewith, a rigid lid closing said container and having said ignition cap being disposed therein, a dome-shaped member secured to the inside of said lid and adapted to repose with its rim on said shaped body disposed in said container, and a resilient cover for said lid held by the walls of said container and adapted, on being struck, to

cause actuation of said striking pin, said striking pin being removably disposed in said resilient cover.

3. An ignition device for oxygen-generating apparatus of the type in which chemical substances generating oxygen by thermal decomposition are employed in the form of a shaped body disposed in a container, said ignition device comprising an ignition cap and a striking pin adapted to coact therewith, a rigid lid closing said container and having said ignition cap disposed therein, a dome-shaped member secured to the inside of said lid and adapted to repose with its rim on said shaped body disposed in said container, and a resilient cover for said lid held by the walls of said container and adapted, on being struck, to cause actuation of said striking pin.

ALBERT HLOCH.
